UNITED STATES PATENT OFFICE.

HALBERT K. HITCHCOCK, OF TARENTUM, PENNSYLVANIA, ASSIGNOR TO PITTSBURGH PLATE GLASS COMPANY, OF PITTSBURGH, PENNSYLVANIA, A CORPORATION OF PENNSYLVANIA.

GRINDING APPARATUS.

1,151,785.

Specification of Letters Patent. Patented Aug. 31, 1915.

Application filed July 28, 1913. Serial No. 781,529.

To all whom it may concern:

Be it known that I, HALBERT K. HITCHCOCK, a citizen of the United States, residing at Tarentum, in the county of Allegheny 5 and State of Pennsylvania, have invented certain new and useful Improvements in Grinding Apparatus, of which the following is a specification.

The invention relates to mechanism for grinding surfaces, particularly of plate glass. It has for its primary objects; (1) the provision of improved means for adjusting the drive of the runners so that their greater abrading action may be directed at 10 any portion of the sheet of glass requiring such action; (2) the provision of improved means for securing the attachment of the runners to and their disengagement from their supporting means, and (3) the provision of compact and efficient means for regulating the pressure of the runners upon the glass being ground, the said means being constructed so as to prevent fracturing the glass due to excessive pressure being concentrated upon the high places by the runners as the glass rotates therebeneath. Certain embodiments of the invention are illustrated in the accompanying drawings, wherein—

Figure 1 is a partial section and partial side elevation showing the general arrangement of the parts, Fig. 2 is an enlarged section taken on the line II—II of Fig. 1, Fig. 2^a is an enlarged detail partially in section 30 of the bypass construction in Fig. 1, Fig. 3 is a section similar to that of Fig. 2, but taken through a modified form of construction, Figs. 4 and 5 are sections taken on the lines IV—IV and V—V respectively of Fig. 40, Fig. 6 is a plan view of the central portion of the runner with the parts for supporting it removed, Fig. 7 is a partial side elevation and partial section showing the general arrangement of another modification 45 of the structure, Fig. 8 is an enlarged section through the spring cylinder and parts contained therein, and Fig. 9 is a partial side elevation and partial section of another modified type of the apparatus.

Referring first to the construction as shown in Figs. 1 and 2; 1 is a portion of the table of the apparatus, which is rotated in the usual way and may be of any approved type; 2 is one of the runners; 3 is the built-up girder or framework from which the run-

ners are suspended, such girder being supported at the ends by means of the uprights 4; 5 is the bar or post by means of which the runner 2 is suspended from the box girder or bridge 3; 6 is a plunger or piston supported upon the lower member of the girder 3; 7 is a cylinder or annular chamber fitting over the plunger or piston 6 and keyed to the post 5; 8 is a pneumatic hydraulic tank from which the cylinder 7 is supplied with fluid through the pipe 9; 10 is a hand-wheel by the operation of which the engagement and disengagement of the post 5 with respect to the runner is secured; and 11 is another handwheel by the actuation of 60 which the rotary adjustment of the post 5 with respect to the runner 2 is secured in order to enable the operator to shift the position of the portion of the runner which bears hardest on the glass during the period 65 when the runner is being lowered and before the total weight is applied, thus increasing and decreasing the drive of the runner at will.

Mounted rotatably in a recess in the center 70 of the runner 2 is the bearing and supporting block 12 around which the runner 2 rotates. This block is held in position in its recess by means of the plate 13 which overhangs the upper edge of the block and is secured to the runner by means of the bolts 14 and 15. The supporting bar or post 5 is rectangular in cross section, and is provided along one side at its lower end with a projecting rib 16 fitting in a groove in the 75 block 12. The rib is held in position in its groove by means of the key 17 having its lower end 18 tapered, and its upper end 19 is turned laterally to receive the screw 20 carried by the handwheel 10. The nut 22 80 just below the end 19 prevents downward movement of the key 17 with respect to the handwheel 10. It will be seen that by operating the handwheel 10 to raise the key 17 the lower end of the key 18 is withdrawn 85 from the socket in the block 12, thus providing room to permit the post 5 to move to the right and release the rib 16 from its groove.

Secured to the upper end of the post 5 90 is the gear 23, such gear being held in position with respect to the upper frame member by means of the nut 24, and being operable from the worm 24 having driving connection with the shaft 25. The shaft 95

25 is operable from the handwheel 11, so that by rotating this handwheel the post 5 and the block 12 may be given any desired degree of rotation. The purpose of this rotation of the post is to secure an adjustment of the drive of the runner 2 with respect to the table 1. The rib 16 is off center with respect to the centerline A of the runner, so that the runner is eccentrically supported, and the side of the runner farthest removed from the rib tends to drop down and bear harder on the glass when the weight of the runner is partially supported on the rib 16, that is, during the 10 starting up of the grinder. By rotating the post 5 and changing the point of eccentric support of the runner, the runner may be made to bear heaviest upon any desired point of the table, thus shifting the driving moments with respect to the center of the runner 2, thereby causing the same to rotate more rapidly or slowly, as may be required in order to grind the surface of the glass straight. There is sufficient lost motion between the lower end of the post 5 and the 15 socket of the block in which it fits to permit of the relatively slight tilting movement of the runner, which accomplishes the result as above described. The depending sleeve 20 7^a gives a very rigid support for the post adjacent the block 12, and the uprights 3^a (Fig. 2) connect the horizontal beams constituting the girder 3.

In order to regulate the amount of pressure between the runner and the glass on the table, the plunger 6 and cylinder 7 are provided, the plunger 6 being supported upon the girders 3, and the cylinder 7 being keyed to the post 5 as indicated at 26 (Fig. 2). Packing 27 for the plunger is provided, and fluid is admitted to the space between the plunger and cylinder through the passage 28 connecting with the pipe 9. The other end of the pipe 9 is connected to the 25 tank 8, and this tank 8 is supplied with water under pressure, by means of the pipe 29 leading to an accumulator or any other desired source of fluid pressure, and controlled by a threeway hand valve (not shown). The space above the water 30 or other liquid in the tank 8, is filled with air and constitutes with respect to the plunger and cylinder an air spring for securing a 35 resilient application of power tending to raise the post 5 and the runner 2 carried thereby. A throttling valve 9^a is placed in the pipe 9 (Fig. 2^a) and serves to regulate the resistance of the water flowing from the cylinder to the tank 8. A by-pass 9^b 40 is provided around the valve and in this pipe is carried a check valve 9^c which permits the water to flow through the by-pass to the cylinder, but prevents movement in the reverse direction. The arrangement allows a free flow of water to the cylinder,

thus permitting the runner to respond promptly to force tending to raise it, while downward movement of the runner is resisted and made more gradual, due to the throttling action of the valve 9^a.

When it is desired to lift the runner from the table, water under pressure is admitted into the chamber 8, reducing the volume of air contained therein until the pressure of the air and water is such that the water 70 acting against the annular cylinder 7 raises the runner 2. When the grinding operation is first started, in order to prevent excessive breakage where the glass has a rough surface, the pressure of the runner upon the 75 glass is applied gradually, such result being accomplished by allowing the escape of some of the water in the tank 8. The runner moves downward until it contacts with the surface of the glass, the air in the tank 80 expanding and reducing the pressure in the tank and cylinder, thus permitting the application of a gradually increasing pressure to the glass. The rate at which the increasing pressure is applied is regulated by the 85 rate at which the water is withdrawn from the tank 8 and can be so adjusted that the pressure on the glass is proportional to the amount of grinding accomplished during the interval in which the increasing pressure has been applied. If desired, the flow of water from the tank may be interrupted at any time, thereby fixing the pressure upon the glass at a substantially constant 90 amount, which pressure increases slightly 95 as the runner rises, and decreases as the runner lowers, due to the unevenness of the surface passing under the runner. After the unevenness of the surface of the glass has been removed, the entire weight of the runner is permitted to rest upon the glass.

It will be seen from the foregoing that the apparatus described provides a very compact and easily operated means for regulating the pressure of the runner upon the 100 glass. The arrangement also tends to eliminate the fractures or cracks which often occur due to the momentum of the runner as it is caused to move up and down by the uneven surface of the glass over which it 105 travels. The plunger and cylinder construction resists any violent downward movement of the runner, as any downward movement of the runner must necessarily cause the expulsion of the liquid in the cylinder 110 above the plunger, and this expulsion of the liquid is resisted by the friction of the liquid flowing through the pipe 9, and by the compressed air above the liquid in the tank 8. This resistance also increases with the extent 115 of downward movement, since the air in the tank 8 is becoming more and more compressed, and therefore more and more 120 resistent. It will also be seen that the runner 125 is free of any counterweight tending to in- 130

crease the momentum of the runner when moved in either direction, so that the momentum of the runner in both directions is reduced to a minimum, and the danger of fracturing correspondingly reduced. Other advantages incident to the construction will be readily apparent to those skilled in the art.

Figs 3 to 6 illustrate a modification of the apparatus just above described. In this construction antifriction rollers 31 and balls 32 are provided to reduce the friction between the supporting block 12' and the socket of the table 2' in which the block is mounted. The construction of the post 5', the key 17', and the operating handwheel mechanism therefor is the same as heretofore described in connection with the structure of Figs. 1 and 2. The means for adjusting the post 5' rotarily, including the gear 23' and worm 24' are the same as heretofore described, as is also the mounting of the plunger 6' and cylinder 7 with respect to the girder and supporting post 5'. The primary distinction of the apparatus of Fig. 3 over that of Figs. 1 and 2 is in the relative arrangement of the plunger and cylinder, and in the means of operation. It will be noted that in the construction of Fig. 3 a very considerable space is provided above the plunger when the cylinder is in lowered position, which is not the case in the construction of Figs. 1 and 2. This difference in arrangement is due to the fact that in the construction of Fig. 3 the space above the plunger is larger and in itself constitutes an air chamber of sufficient volume to give the resilient support, and during the operation of supporting or partially supporting the runner contains both air and water. The passage 28' is connected directly to an accumulator or other source of liquid pressure, and this liquid supplied to the pipe 28' serves to compress the air above the plunger 6'. The air spring or cushion is in this construction therefore located in the cylinder instead of in a separate tank as in the construction of Figs. 1 and 2. It will be seen that the apparatus is somewhat simpler and more direct in its operation than that of Fig. 1, and that the water supplied at the top of the plunger serves as a packing means. By proportioning the ratio of the air space to the water space, it is possible to regulate the changes in pressure due to the movement of the runner toward and away from the glass. For instance the larger the air space the less will be the variation in pressure due to the oscillation of the runner up and down. The resistance secured by the plunger and cylinder arrangement of Fig. 3 is also more resilient than that of the construction of Figs. 1 and 2, since there is no outflow of water through the passage 28' as is the case in the apparatus of Figs. 1 and 2, a part of

the resistance to the downward movement of the cylinder 7 in the construction of Figs. 1 and 2 being due to the resistance to the flow of the water through the small pipe 9 and past the throttling valve 9^c, such arrangement preventing a too free oscillation of the runner.

In the modified type of apparatus illustrated in Figs. 7 and 8, the two runners 2² 2² are supported over the table 1² upon the supporting bars or posts 5², the construction on the two sides of the table being precisely the same, aside from the size of the runners, so that a description of one runner and its supporting means will be sufficient. The framework 3² which supports the runners is of the usual type, being carried at the ends by the uprights 4², and carrying the fulcrum brackets 33. The supporting post or bar 5² for the runner is circular in cross section and is journaled in bearings 34 and 35 carried by the frame 3², and the downward thrust of the post is carried by the block 36 pinned to the upper end of the post. Below the block 36 is a bearing member 37 for taking the thrust of the block 36, antifriction balls being preferably interposed between the two bearing surfaces. The bearing member 37 is mounted loosely for rocking movement in the end of the lever 38. A fluid pressure cylinder 39 operating the piston rod 40 hooked to the lever 38 serves as a means for lifting the runner free from the table when it is desired to move the table from beneath the runner after the grinding operation is completed. At other times no fluid is supplied to the cylinder 39, so that the movement of the lever 38 is not affected during the grinding operation by the connection 40.

The means employed for regulating the pressure of the runner upon the glass comprises the connecting rod 41, the connecting rod 42, the cylinder 43 carried by the connecting rod 42, the spring 44 in the cylinder, and the handwheel 45 provided with nut 46 engaging the threaded portion of the connecting rod 42. The connecting rod 41 is in two parts pivoted together at 47, and the lower portion of the rod is provided with a head 48 engaging the lower side of the spring 44. The cylinder is of course free of attachment to the frame, and the portion of the connecting rod in the cylinder slides freely through the bearing portion 49 (Fig. 8).

After the previous grinding operation is completed the runner is raised by means of the cylinder 39 and the handwheel 45 is turned until the runner is held suspended by the reaction of the spring 44, at which time the fluid pressure in the cylinder 39 is released. When it is desired to start the grinding operation on the next set the handwheel 45 is gradually turned allowing the

runner to move down and come in contact with the glass. As the grinding progresses the handwheel 45 is turned to allow the connecting rod 42 to move up, thus reducing the compression of the spring and allowing more and more of the weight of the runner to press upon the glass. It will be seen that the spring in this construction performs precisely the function of the compressed air in the construction of Figs. 1 and 3, that is, the spring applies a yielding resistance to the downward movement of the runner, and such resistance increases as the downward movement progresses. The tendency of the runner to move down suddenly and fracture the glass is thus resisted as in the other types of apparatus. It will also be seen that the adjustment of the yielding resistance by means of the handwheel 45 corresponds in function to the adjustment secured by the valves in the constructions of Figs. 1 and 3, as such valves control the compression of the air by the water, and the air is the equivalent of the spring.

25 In the modification illustrated in Fig. 9, 1² is the table, 2² is the runner, 5² is the supporting post, 38² is the lever for supporting and operating the runners, and 33² is the fulcrum bracket for the lever 38². The supporting post 5² is preferably of the type shown in Fig. 2, and is rotated to secure the tilting adjustment of the runners by means of the handwheel 11² connecting with the post 5² by means of gearing corresponding to that in Figs. 1 and 2. The upper end of the post is keyed to a thrust bearing member 36² whose flange is supported by the opposing thrust bearing member 37², anti-friction balls being interposed between the thrust surfaces. The thrust bearing member 37² is connected to the lever 38² by means of the link 50, while the other end of the lever 38² is connected to a connecting rod 41² similar to that of Fig. 7 and working in a cylinder 43² with a spring 44² therein similar to the corresponding parts in Fig. 7. The cylinder 43² is pivoted at its lower end to another connecting rod 42², such rod constituting the piston rod for the piston 51 working in the hydraulic cylinder 52. The cylinder is secured rigidly to a bracket 53 carried by the framework of the apparatus, and movements of the piston 51 are controlled by means of a three-way valve connected to the pipe 54 leading to the upper side of the piston. The cylinder and piston 51-52 constitute a means for regulating the tension of the spring 44², such parts taking the place of the nut and screw connection in Fig. 7, for adjusting the position of the connecting rod 42. The actuation of the three-way valve in the pipe 54 constitutes a convenient means for adjusting the position of the piston 51, and aside from the fact that this valve is operated instead of the hand-

wheel 45, the operation of the apparatus is the same as heretofore described in connection with Fig. 7.

What I claim is—

1. In apparatus for grinding, a rotating table for carrying the member to be ground, a runner mounted above the table, resilient resistance means opposing the downward movement of the runner during the grinding operation, and means for regulating the yielding resistance means during the grinding operation.

2. In apparatus for grinding, a rotating table for carrying the member to be ground, a runner mounted above the table, resilient compression means tending to reduce the pressure of the runner upon the member during the grinding operation, and means for varying the force exerted by the said means during the grinding operation.

3. In apparatus for grinding, a rotating table for carrying the member to be ground, a runner mounted above the table, resilient means placed under stress during the grinding operation and tending to oppose the downward pressure of the runner due to its weight, and means for decreasing the stress and permitting more and more of the weight of the runner to be applied to the member as the grinding progresses.

4. In apparatus for grinding, a rotating table for carrying the member to be ground, a runner mounted above the table, and yielding pneumatic means opposing the downward movement of the runner and removing a portion of the weight thereof from the member being ground.

5. In apparatus for grinding, a rotating table for carrying the member to be ground, a runner mounted above the table, yielding pneumatic means opposing the downward movement of the runner and removing a portion of the weight thereof from the member being ground, and means for varying the opposing force exercised by the said pneumatic means.

6. In apparatus for grinding, a rotating table for carrying the member to be ground, a runner mounted above the table, yielding pneumatic means opposing the downward movement of the runner and removing a portion of the weight thereof from the member being ground, and means for supplying liquid under pressure for varying the opposing force exercised by the said pneumatic means.

7. In apparatus for grinding, a rotating table for carrying the member to be ground, a runner mounted above the table, a pneumatically operated ram for opposing the downward movement of the runner and removing a portion of the weight thereof from the member being ground, and means for supplying liquid under pressure to the interior of the ram to compress the gas

- therein and increase the lifting power of the ram.
8. In apparatus for grinding, a rotating table for carrying the member to be ground, a runner mounted above the table, a post for supporting the runner, resiliently operated means concentric with the post for applying force thereto tending to lift the runner, and means for varying the force applied by the resilient means.
9. In apparatus for grinding, a rotating table for carrying the member to be ground, a runner mounted above the table, a post for supporting the runner, and a fluid operated lifting ram concentric with the post for applying force thereto tending to lift the runner.
10. In apparatus for grinding, a rotating table for carrying the member to be ground, a runner mounted above the table, a post for supporting the runner, and a fluid operated lifting device comprising a cylinder and piston concentric with the post with one of said parts fixed against movement and the other secured to the post and adapted to apply lifting force to the post when fluid is supplied to the interior of the cylinder.
11. In apparatus for grinding, a rotating table for carrying the member to be ground, a runner mounted above the table, a post for supporting the runner, and a fluid operated lifting device for the post comprising a cylinder and piston, an air chamber containing a liquid connected to the lifting device, and means for supplying liquid under pressure to the said air chamber to compress the air therein and vary the lifting force exerted by the device.
12. In apparatus for grinding, a rotating table for carrying the member to be ground, a runner mounted above the table, resilient resistance means opposing the downward movement of the runner, and fluid pressure controlling means for regulating and varying the stress of the said resilient resistance means.
13. In apparatus for grinding, a rotating table for carrying the member to be ground, a runner above the table, a post held against rotary movement with the runner, a supporting thrust bearing carried by the lower end of the post, and an opposing thrust bearing carried by the runner above the said supporting thrust bearing.
14. In apparatus for grinding, a rotating table for carrying the member to be ground, a runner above the table provided at its center with a bearing recess, a post held against rotary movement with the runner, a bearing block carried detachably upon the lower end of the post and held against rotative and vertical movement with respect to the said post and having a thrust bearing surface on its upper face, and a lateral bearing surface around its periphery opposing the side walls of the said recess, and a thrust bearing carried by the table above the block and opposing the bearing surface on the block.
15. In apparatus for grinding, a rotating table for carrying the member to be ground, a runner above the table, a post held against rotary movement with the runner, a supporting thrust bearing carried by the lower end of the post, an opposing thrust bearing carried by the runner above the said supporting thrust bearing, and means whereby the post may be disengaged from the supporting thrust bearing.
16. In apparatus for grinding, a rotating table for carrying the member to be ground, a runner above the table, a post held against rotary movement with the runner, lateral and thrust bearings carried at the central portion of the runner, and opposing lateral and thrust bearings carried by the lower end of the said post.
17. In apparatus for grinding, a rotating table for carrying the member to be ground, a vertical post supported above the table and held against lateral and rotary movement, a runner swiveled upon the lower end of the post, and means for raising and lowering the post and the runner carried thereby.
18. In apparatus for grinding, a rotating table for carrying the member to be ground, a vertical post supported above the table and held against lateral and rotary movement, a runner swiveled upon the lower end of the post, and power means intermediate the ends of the post for moving it vertically.
19. In apparatus for grinding, a rotating table for carrying the member to be ground, a vertical post supported above the table and held against lateral and rotary movement, a runner swiveled upon the lower end of the post, and a fluid operated ram having its piston and cylinder concentric with the post for raising such post and the runner carried thereby.
20. In apparatus for grinding, a rotating table for carrying the member to be ground, a vertical post suspended above the table and held against lateral and rotary movement, a runner above the table, a lateral and thrust bearing block supported by the lower end of the post off center with respect to the center line of the post and nonrotatable with respect to the post, lateral and thrust bearings carried by the runner in opposition to the lateral and thrust bearings of the block, and means whereby the post may be adjusted rotarily about the center line.
21. In apparatus for grinding, a rotating table for carrying the member to be ground, a vertical post suspended above the table and held against lateral and rotary movement, a runner above the table, a bearing block on which the runner is swiveled concentrically, a supporting connection between the post and block off center with respect to the axis of

rotation of the block, and means whereby the post may be adjusted rotarily.

22. In apparatus for grinding, a rotating table for carrying the member to be ground, 5 a runner above the table, means for suspending the runner off center causing a tendency to tilt, and means for adjusting the off center point of support rotarily about the axis of rotation of the runner.

10 23. In apparatus for grinding, a rotating table for carrying the member to be ground, a runner above the table, a block upon which the runner is swiveled provided with a vertical recess and with another recess extending 15 laterally from said vertical recess, a post having its lower end engaging the recess and partially filling it with a projection engaging the lateral recess, and a vertically movable key slidable along the post and fitting 20 into the space in the vertical recess alongside the end of the post.

24. In apparatus for grinding, a rotating table for carrying the member to be ground, a runner above the table, a block 25 upon which the runner is swiveled provided with a vertical recess and with another recess extending laterally from said vertical recess, a post supported intermediate its ends and with its lower end engaging and 30 partially filling the vertical recess and provided with a projection engaging the lateral recess, and a vertically movable key extending longitudinally of the post and operable from the upper end thereof and fitting 35 at its lower end into the space in the vertical recess alongside the end of the post.

25. In apparatus for grinding, a rotating table for carrying the member to be ground, a runner above the table, a block upon 40 which the runner is swiveled provided with a vertical recess, a non-rotatable post supported from above and having its lower end engaging the said recess non-rotatably, interengaging means carried by the lower 45 end of the post and the block whereby the block and runner are held against downward movement with respect to the post after the said means are interengaged, and a locking device for locking the post against 50 movement tending to disengage the said means.

26. In apparatus for grinding, a rotating table for carrying the member to be ground, a lifting ram for regulating the movements

of the runner toward and from the table, a 55 closed receptacle carrying a liquid and having an air chamber, a connection for supplying liquid from the receptacle to the ram, and means for supplying liquid under pressure to the receptacle to vary the air pressure in the said air chamber.

27. In apparatus for grinding, a rotating table for carrying the member to be ground, a lifting ram for regulating the movements of the runner toward and from the 65 table, a closed receptacle carrying a liquid and having an air chamber, a throttling connection between the ram and the receptacle for conveying liquid to and from the ram, and means for supplying liquid under 70 pressure to the receptacle to vary the air pressure in the said air chamber.

28. In apparatus for grinding, a rotating table for carrying the member to be ground, a lifting ram for regulating the movements 75 of the runner toward and from the table, a closed receptacle carrying a liquid and having an air chamber, a throttling connection between the ram and the receptacle for conveying liquid to and from the ram and arranged to permit a relatively free flow of liquid to the ram but to throttle the fluid as it returns to the receptacle, and means for supplying liquid under pressure to the receptacle to vary the air pressure in the said 80 air chamber.

29. In apparatus for grinding, a rotating table for carrying the member to be ground, a lifting ram for regulating the movements of the runner toward and from the 90 table, a closed receptacle carrying a liquid and having an air chamber, a connection for supplying liquid from the receptacle to the ram, a throttling valve therein, a bypass with a check valve permitting liquid 95 to pass the valve in its movement to the ram, but preventing the reverse movement through the bypass, and means for supplying liquid under pressure to the receptacle to vary the air pressure in the said air 100 chamber.

In testimony whereof I have hereunto signed my name in the presence of the two subscribed witnesses.

HALBERT K. HITCHCOCK.
